UNITED STATES PATENT OFFICE.

CHAUNCEY G. HOBART, OF CHICAGO, ILLINOIS.

CARD-FILING DESK.

Application filed November 23, 1921. Serial No. 518,347.

To all whom it may concern:

Be it known that I, CHAUNCEY G. HOBART, a citizen of the United States, residing at Chicago, in the county of Cook and 5 State of Illinois, have invented a certain new and useful Improvement in Card-Filing Desks, of which the following is a specification.

In large offices a filing clerk having a 10 large number of cards or other documents to take care of, has heretofore been equipped with a writing table, desk, or other suitable device, bordered by side tables or cases containing card drawers or boxes. Under 15 these conditions, when the operator needs to write on a card in, or file a new card in one of the sets of cards, it is necessary to move the card container from its side position onto the desk in front of the operator; 20 there perform the filing operation, and then return that particular card container to its place at the side of the desk. As successive cards handled are apt to be located on opposite sides of the desk, this operation 25 requires a pivoting action by the operator accompanied by repeated lifting of the heavy boxes of cards, thus causing a needless consumption of both strength and time. In order to remove these objections just pointed out, the device of this invention has been 30 perfected to in actual test reduce the labor and consequent expense of such a filing system about thirty per cent.

The object of the invention is to provide 35 a device capable of attaining the above result.

The invention consists in providing a desk with top perforations for the reception 40 of cards so supported that their tops are only slightly below the upper surface of the table, in the particular case illustrated, with permanently attached boxes below the surface of the desk and in register with said 45 openings, whereby when the table is loaded with cards the top of the table is still substantially flat for the reception of large flat documents, while every card is accessible to the operator sitting in central position in front of the desk. The invention 50 further consists in many features and details of construction, hereafter more fully set forth in the specification and claims.

Referring to the drawings in which like numerals denote like parts throughout the 55 several views,

Figure 1 is a perspective view of a desk

illustrating this invention in its preferred form.

Figure 2 is a plan view of the desk of 60 Figure 1.

Figure 3 is a sectional detail view with a card compartment on the line 3—3, Figure 2.

The device may be applied to any conventional desk 10 having a top 12 before which 65 the operator sits in central position 14. The particular desk shown happens to have vertical sets of drawers 16 and 18 on opposite sides of the operator.

The top 12 of the desk is provided with 70 a plurality of oblong perforations 20, 22, 24, 26, 28 and 30 arranged as near as may be radially of the central position occupied by the operator in front of the desk. Below each one of these perforations is a card 75 supporting device which in the particular case here illustrated takes the form of a permanent card box 32, adapted to receive the filing cards 34 of conventional construction, and preferably but not necessarily 80 adapted to be closed by a removable cover 36. In the particular case here illustrated the cards 34 are of such a height that when bunched in normal position, as shown, they extend up to the bottom face of the cover 85 36, when in place. If, however, it is not desired to use the cover 36, taller cards may be used so that they extend up to approximately the upper flat surface of the desk 90 top 12.

In the operation of the device, the various compartments 20-30 inclusive are partially or wholly stocked with cards. The operator now takes his or her place in front of the desk, and in the ordinary manner removes a single card for notation thereon, placing it meanwhile on the central flat area 38 of the desk, or if additional cards are to be filed, inserts them in the various proper compartments 20-30 as may be required. 95

Owing to the fact that the cards do not extend above the surface of the desk, the operator can spread over the desk, except at the particular point where a card is being inserted or removed, large flat papers, 105 such as maps or drawings, without interference by the cards in the various receptacles, a thing which would be impossible where one or more boxes of cards are placed on top of a flat desk, as in previous practice. 110

When the covers 36 are provided and no filing is to be done, these covers may be put

in place and the desk used like any ordinary flat desk.

The device is most readily adaptable to cards of any size, but is by no means limited to either the size or material of ordinary filing cards.

Having thus described my invention, what I claim as new and desire to secure by Letters Patent is:

10. 1. In a device of the class described, a normally flat top desk, provided with a plurality of elongated surface perforations arranged radially about a user's position adjacent to the desk, each adapted to hold a plurality of vertically disposed filing cards positioned with their top edges normally lying in a horizontal plane, adjacent to the upper surface of the desk, so as to be readily accessible through said perforations in the top of the desk, and means for so supporting said cards.
15. 2. In a device of the class described, a

normally flat top desk, provided with a plurality of elongated surface perforations arranged radially about a user's position adjacent to the desk, each adapted to hold a plurality of vertically disposed filing cards positioned with their top edges normally lying in a horizontal plane, adjacent to the upper surface of the desk, so as to be readily accessible through said perforations in the top of the desk, means for so supporting said cards, and a cover insertable in each of said perforations adapted to render the top 25 of the desk a flat, continuous working surface whenever the cards are not in use.

In witness whereof, I have hereunto subscribed my name in the presence of two witnesses.

CHAUNCEY G. HOBART.
